UNITED STATES PATENT OFFICE.

FRANK M. ASHLEY, OF NEW YORK, N. Y.

FOUNTAIN-PEN.

1,111,519.

Specification of Letters Patent. Patented Sept. 22, 1914.

Application filed September 7, 1911. Serial No. 648,007.

To all whom it may concern:

Be it known that I, FRANK M. ASHLEY, a citizen of the United States, and a resident of New York city, borough of Brooklyn, in the county of Kings and State of New York, have invented certain new and useful Improvements in Fountain-Pens, of which the following is a specification.

My invention relates to fountain pens and 10 one object of my invention is to provide a fountain pen having a valve located near its front end by means of which the passage through which ink flows from the reservoir to the pen may be closed in a simple and 15 efficient manner.

A further object is to provide a construction in combination with said valve by means of which the reservoir may be filled with ink.

20 A further object is to provide a fountain pen in which there are no joints in the casing which come in contact with the fingers when the pen is held as in the act of writing, and soil the fingers of the writer in case the 25 reservoir should leak at said joint.

A further object is to provide a valve construction which will not easily stick and become inoperative by reason of the ink drying between the movable parts of the valve.

30 A further object is to provide a fountain pen in which there are no threaded joints at the forward end thereof.

Referring to the drawings, Figure 1 is a longitudinal sectional view of a fountain pen embodying one form of my improved valve construction. Fig. 2 is a similar view embodying a slightly modified form of valve, and also the self-filling devices in combination therewith. Fig. 3 is a similar 40 view and construction to that shown in Fig. 2, except that the pen section does not abut an inner shoulder formed integral with the casing.

Referring to Fig. 1, 10 indicates a casing 45 having a reservoir 11 closed at its rear end by a cap 12 which is fastened to the casing by screw threads. The casing 10 is provided with a cylindrical bore 13 which extends from the front end of the casing toward the 50 rear end thereof for a short distance to a shoulder 14 at which point a smaller cylindrical bore 15 communicates with the reservoir 11. Fitted to slide snugly in the bore 15, is a plug 16 provided with an ink-duct 55 17 of the same width and depth as the ink-

duct 18 formed in the feed-plug 21, which ink-duct is of the usual form and dimensions commonly used in fountain pens.

The cylinder 19 may have a smooth outer surface as illustrated or may have its outer surface formed as illustrated in Fig. 2, and is fitted to closely fit the inner surface of the bore 13 to slidingly engage said surface, and is of a thickness corresponding to the height of the shoulder 14, and abuts said shoulder 60 as illustrated, and is provided at its front end with an annular flange 20 which preferably abuts the end of the casing 10 and is of sufficient width to be grasped between the thumb and fore-finger to turn the cylinder 65 70 in the bore 13.

The feed-plug 21 fits closely in the cylinder 19 and is of the same diameter as the plug 16 and abuts said plug so that ink may flow from the reservoir 11 through the ink-ducts 17 and 18 to the pen 22 when said ink-ducts are in alinement with each other. By 75 rotating the cylinder relative to the casing the ink-ducts are thrown out of alinement and the valve, comprising the plug 16, cylinder 19 and feed-plug 21, closed. To provide for adjustment of the pen 22, the feed-plug may be moved longitudinally in either direction relative to the casing and the plug 16 moved to correspond and abut the feed-plug to form the valve; as will be easily understood by those skilled in this art. 80

Referring now to Fig. 2, the difference in this construction from that of Fig. 1 is, that instead of the front end of the cylinder 19 terminating in a flange like that indicated by 20 in Fig. 1, it is provided with a tapering end as illustrated and indicated by 23. Fig. 2 also contains the self-filling construction comprising a small tube 24 which is connected to and extends through the plug 16, its forward end being shown as closed by the rear end of the feed-plug 21 when the ink-ducts 17 and 18 are in alinement, and its opposite end located near the rear end of the 90 reservoir. The inner diameter of the reservoir is reduced to provide a bore 25 in which is held one end of a soft rubber sack 26 by means of a hard rubber nipple 27 the outer surface of which is formed cone-shaped and of proper diameter to be inserted in the sack and clamp the sack against the casing. A cap 28 covers the sack and is threaded to the end of the casing at 29. 95

The cylinder 19 is provided with a plu- 110

rality of concentric grooves 30—30, etc., placed close together to provide bearing surfaces of limited area in contact with the surface of the bore 13 to reduce the friction and danger of sticking in case ink gets in the joint lubricating material such as graphite or stiff grease may be inserted in these grooves which thus further reduces the friction and effectually prevents the leaking of the ink past the joint, particularly inasmuch as the writing fluid and the lubricating material do not mix.

The construction illustrated in Fig. 3 is the same as that illustrated in Fig. 2, except that the plug 16 is of the same diameter as the bore 13 and the shoulder 14 is dispensed with.

In all of the forms I have disclosed, there is only one joint at the bottom end of the barrel, which joint is located close to the end of the barrel so as to avoid the possibility of soiling the fingers. The cylinder is elongated sufficiently to obtain a long contacting surface engaging with the bore and thus the possibility of leaking at the joint is obviated.

The operation of filling the reservoir with ink is as follows: First rotate the cylinder until the ink-duct 19 is in alinement with the tube 24, then remove the cap 28 and place the front end of the cylinder beneath the surface of the ink and then collapse the sack 26 by pressing between the thumb and fore-finger to expel a volume of air equal to the capacity of the sack, through the tube and ink-ducts to the atmosphere, then allow the sack to expand, thereby drawing ink through the ink-ducts and tube and into the reservoir where it is trapped. By repeating this operation a few times the reservoir is filled and when full the ink can be felt in the sack or pump. By turning the cylinder a $\frac{1}{4}$ turn the reservoir is closed and no ink can escape therefrom. By turning the cylinder $\frac{1}{2}$ turn from its filling position, the ducts are brought in alinement and the pen may then be used for writing.

Having thus described my invention, I claim as new:

50 1. A fountain pen comprising a casing having a reservoir formed therein and provided with a bore at its forward end and having a partition between said bore and the reservoir provided with an ink-duct, a cylinder fitted to rotate in said bore, and a longitudinally movable feed-plug fitted snugly in said cylinder and extending therethrough, the rear end of said plug closely abutting said partition and having an ink-duct formed in one side thereof adapted to register with the ink-duct in said partition in one position of rotary adjustment, and to be out of registry with the ink duct in the partition in another position of rotary adjustment, the joint between the cylinder and barrel being

close to the end of the barrel, the latter being free from joints at intermediate points of its length.

2. A fountain pen comprising a casing having a reservoir formed therein and provided with a bore at its forward end and having a longitudinally movable partition between said bore and the reservoir provided with an ink-duct, a cylinder fitted to rotate in said bore, and a feed-plug fitted snugly in said cylinder, the rear end of which closely abuts said partition and having an ink-duct formed in one side thereof adapted to register with the ink-duct in said partition in one position of rotary adjustment, and to be out of registry with the ink duct in the partition in another position of rotary adjustment, the joint between the cylinder and barrel being close to the end of the barrel, the latter being free from joints at intermediate points of its length.

3. A fountain pen comprising a casing having a reservoir formed therein and provided with a bore at its forward end and having a partition between said bore and reservoir which is provided with an ink-duct and an opening which extends therethrough and each of which is located an equal distance radially from the axis of said bore, a cylinder fitted to rotate in said bore, a feed-plug fitted in said cylinder, the rear end of which abuts said partition and having an ink-duct formed in one side thereof adapted to register alternately with the ink-duct and opening in said partition, a tube communicating with said opening and extending into said reservoir to near the rear end thereof, and means for drawing ink into said reservoir through said tube and expelling the air therefrom.

4. A fountain pen comprising a casing having a reservoir formed therein and provided with a bore at its forward end and having a longitudinally movable partition between said bore and reservoir which is provided with an ink-duct and an opening which extends therethrough and each of which is located an equal distance radially from the axis of said bore, a cylinder fitted to rotate in said bore, a feed-plug fitted in said cylinder, the rear end of which abuts said partition and having an ink-duct formed in one side thereof adapted to register alternately with the ink-duct and opening in said partition, a tube communicating with said opening and extending into said reservoir to near the rear end thereof, and means for drawing ink into said reservoir through said tube and expelling the air therefrom.

5. A fountain pen comprising a casing having a bore at one end, a cylinder fitted in said bore, a feed-plug having an ink duct within said cylinder, a partition in the casing against which the feed-plug is adapted

- to abut, said partition having an ink duct therein, the cylinder being movable within the bore so as to bring the ink duct of the plug into and out of alinement with the ink duct in the partition, said cylinder being formed with peripheral grooves adapted to receive a lubricant to provide an ink tight yet free fit for the cylinder within the bore, the joint between the cylinder and barrel 5 being close to the end of the barrel, the latter being free from joints at intermediate points of its length.
6. A fountain pen comprising a casing having a reservoir formed therein and provided 15 with a bore at its forward end, an adjustable partition between said bore and reservoir which is provided with an ink-duct and an opening which extends therethrough and each of which is located an equal distance 20 radially from the axis of said bore, a cylinder fitted to rotate in said bore, a feed-plug fitted in said cylinder, the rear end of which abuts said partition and having an ink-duct formed in one side thereof adapted to register 25 with the ink-duct and opening in said partition, a tube communicating with said opening and extending into said reservoir to near the rear end thereof, and means for drawing ink into said reservoir through said 30 tube and expelling the air therefrom.
7. A fountain pen comprising a casing having a reservoir formed therein, and provided with a bore at its forward end, a frictionally held longitudinally movable partition 35 between said bore and reservoir and provided with an ink duct, and an adjustable feed-plug mounted in said bore, said feed plug having an ink-duct formed therein, and adapted to register with the ink-duct in said partition, in one position of 40 rotary adjustment and to be out of registry with the ink duct in said partition in another position of rotary adjustment, so as to constitute a valve.
- 45 8. A fountain pen comprising a barrel having a reservoir therein, a rotatable cylinder frictionally held in one end of said barrel and freely removable therefrom, a feed plug in said cylinder extending therethrough and provided with an ink duct at one side 50 of its axis, an abutment located in said barrel and frictionally held therein in longitudinally adjustable relation to said feed plug and abutting same and having a perforation 55 communicating with the reservoir and with said ink duct.
9. A fountain pen comprising a barrel having a reservoir therein, a rotatable cylinder frictionally held in one end of said barrel and freely removable therefrom, a feed 60 plug in said cylinder extending therethrough, an abutment in said barrel in contact with said feed plug, both having an ink duct arranged in alinement with each other and in communication with said reservoir 65 at one side of the axis of said feed plug and abutment, said feed plug being rotatable relative to the abutment to control the flow of ink from the reservoir to the pen.
10. A fountain pen comprising a barrel 70 having a reservoir formed therein, and provided with a bore at its forward end, a longitudinally movable partition between said bore and reservoir provided with an ink duct through the upper portion thereof, a 75 feed plug frictionally held in said bore and freely rotatable therein abutting said partition, said feed plug being provided with an ink duct at its upper side adapted to aline with the ink duct in the partition to form one straight continuous ink duct between the reservoir and the pen in one position of 80 rotary adjustment and to be out of alinement with the ink duct in the partition in another position of rotary adjustment to cut off the flow of ink from the reservoir to the pen.

Signed at New York city, in the county of New York and State of New York this 6th day of September A. D. 1911.
